Application April 2, 1946, Serial No. 658,894

1 Claim. (Cl. 250—27)

1 This invention relates to improved methods of and means for operating superregenerative receivers. Application of the principles and methods disclosed herein is made, for example, in connection with the radio ranging systems described and claimed in copending applications of William E. Bradley and of Wilson P. Boothroyd and Albert L. Free, Serial Number 651,398, filed March 1, 1946, now Patent No. 2,536,346, issued January 2, 1951, and Serial Number 651,888, filed March 4, 1946, now Patent No. 2,536,488, issued January 2, 1951, respectively. It is, however, to be understood that the invention is not restricted to use in those particular systems, but is applicable to superregenerative receivers generally and may be used to effect a substantial improvement in their operation.

The principal object of the invention is to provide methods of and means for increasing the band width and sensitivity of superregenerative receivers. Another object of the invention is to provide a circuit capable of taking advantage of such improved band width and sensitivity by making it possible to obtain the maximum discrimination between the outputs of a superregenerative receiver in the presence and in the absence of an applied input signal. Other features and advantages of the invention will become apparent after consideration of the following description and the drawings in which:

Figure 1 illustrates a superregenerative receiver adapted to operate in accordance with the principles of the invention.

Figures 2 and 3 are diagrams which will be referred to in explaining the principles and mode of operation of the invention.

Figure 4 is a schematic diagram of a superregenerative receiver which may be made to operate in accordance with the principles of the invention by the application of an unquenching wave form of suitable shape, hereinafter to be defined.

Referring now to Figure 1, the superregenerative receiver shown comprises a triode 1 and a resonant tank circuit 2 comprising inductor 3 and condenser 4. Tank circuit 2 may be tuned to any desired frequency (e. g., 60 megacycles per second) and determines the frequency at which the superregenerator will oscillate. A portion of inductor 3 is made common to both grid and plate circuits of triode 1 in order to provide the necessary mutual coupling required for oscillation. Received signals intercepted by antenna 5 are supplied to tank circuit 2 through the medium of mutual coupling between in-

ductors 3 and 6. Also coupled to tank circuit 2 through inductor 7 is a damping circuit comprising serially and oppositely connected diodes 8 and 9. Between the plates of these diodes 5 and a center tap on inductor 7 is provided a connection including condenser 10 for by-passing signal frequencies within the range of oscillation of the superregenerator. To the plates of diodes 8 and 9 are supplied periodically recurring 10 negative unquenching pulses of the form shown at A in Figure 2. The duration of such pulses may be, for example, of the order of 35μ seconds and they may be recurrent at almost any desired frequency, the frequency of recurrence 15 having no appreciable effect on the operation of the circuits in accordance with the invention. Diodes 8 and 9 may be biased, by the application of a voltage derived across resistor 11 of a voltage divider comprising resistors 11 and 12, 20 so as to cause them normally to conduct and introduce damping into tank circuit 2 of the superregenerative oscillator. At the same time the magnitude of this bias, as compared with the magnitude of negative unquenching pulses, 25 should be such that upon the occurrence of an unquenching pulse, diodes 8 and 9 will cease to conduct, thereby removing the damping from tank circuit 2 and permitting oscillations to build up therein. Further limitations on the 30 value of this bias in accordance with the present invention will be set forth hereinafter. The diode quenching arrangement shown is particularly advantageous since it avoids shock excitation of the oscillator tank circuit, inasmuch as 35 surge currents flow from each end of damping inductor 7 and therefore tend to cancel. This circuit is described and claimed in copending application of William E. Bradley, Serial Number 660,037, filed April 6, 1947.

40 Further in accordance with the invention the grid of triode 1 is grounded through grid leak resistor 13 and diode 14, the latter being connected in the polarity shown. A connection, including an RC circuit comprising resistor 15 and 45 condenser 16, is also provided between the common plates of diodes 8 and 9 and the plate of diode 14. The purpose of these connections will be explained later in this specification. Output 50 from tank circuit 2 during the unquenched intervals of the superregenerative oscillator may be derived by means of a counter circuit comprising condenser 17, diodes 18 and 19, condenser 20 and resistor 21. The mode of operation of this circuit will be described in detail 55 hereinafter.

I have discovered that in order to secure wide band operation in a superregenerative receiver, it is essential that the net conductance of the oscillator circuit be changed as rapidly as possible from a large positive value to a large negative value, in other words the change from complete quenching to complete unquenching of the oscillator tank circuit should be made in as short a time as possible. Assume for the moment that, in the circuit of Figure 1, the bias for diodes 8 and 9 is provided solely by the RC circuit comprising resistor 11 and condenser 22 (i. e. that resistor 12 of the voltage divider 11, 12 is not connected to an external source of biasing voltage). Assume further that the grid of triode 1 is connected directly to ground through grid leak 13 and that both diode 14 and the connection, comprising RC circuit 15, 16, between the plates of diodes 8 and 9 and the plate of diode 14 is omitted. Exaggerating the imperfections inherent in the leading edge of the negative unquenching pulse shown at A in Figure 2, it may appear as shown in Figure 3. The leading edge will have a finite slope, and the upper and lower corners will be somewhat rounded as shown. Assuming the quenching wave form to vary from a value of 250 volts positive (corresponding to quenching) to a value of 180 volts positive (corresponding to unquenching), there will normally be developed across condenser 22 a biasing voltage of approximately +250 volts which will be applied to the cathodes of diodes 8 and 9 and will permit them normally to conduct and introduce damping into tank circuit 2. As the quenching voltage falls from 250 volts by an amount ΔE (which may be of the order of 5 volts), the change in the tank circuit from its quenched to its unquenched condition will take place during an interval ΔT , which owing to the gradual change in slope of the quench wave form as represented in Figure 3, may not be sufficiently short to yield the desired wide band-width. By applying to the cathodes of diodes 8 and 9, through the medium of voltage divider 11, 12, a somewhat less positive bias (e. g. +245 volts), the change from the quenched to the unquenched condition, corresponding to the change ΔE , may be made to take place in an appreciably shorter interval $\Delta T'$ as illustrated in Figure 3. This diminution in the time required for unquenching will result from operating on the steeper portion of the quench wave form. Thus, by properly adjusting the bias on diodes 8 and 9, two objectives may be achieved; first, the unquenching of the superregenerator may be made to occur more rapidly, and secondly, the exact time of unquenching may be controlled within limits by varying the bias.

The effect of changing the net conductance of the oscillator circuit from a large positive to a large negative value at the inception of the unquenched interval will be to cause oscillations to build up in the oscillator tank circuit more rapidly than they otherwise would, both in the presence as well as in the absence of signals applied to tank circuit 2 from an external source such as antenna 5. However, the rate of exponential buildup will also vary, depending upon the magnitude, if any, of such signal present in the tank circuit at the time of unquenching. In the absence of any such signal, oscillations in the tank circuit might build up to an amplitude a corresponding to tube overload during an interval T_1 as illustrated at B in Figure 2. Oscillations in tank circuit 2 would then continue at this amplitude during the remainder of the unquenched in-

terval T_4 . On the other hand, with some signal present in tank circuit 2 at the time of unquenching, buildup to tube overload would occur in a time substantially less than T_1 , as illustrated at C in Figure 2. In this instance likewise, once having built up to overload amplitude, oscillations would continue in the tank circuit throughout the unquench interval of duration T_4 .

The principal effect of permitting oscillations to continue in the tank circuit, after they have reached an amplitude sufficient to produce overload in triode 1, is to reduce the percentage difference between the envelopes of the oscillations in tank circuit 2 corresponding respectively to absence and presence of signal in the tank circuit at the time of unquenching. This will be apparent from a comparison of B and C in Figure 2. Thus, using a cycle counter of the sort shown in Figure 1 to distinguish between the outputs from the superregenerative oscillator in the presence and in the absence of received signal, it will be more difficult to distinguish received signal from noise (i. e. the sensitivity of the receiver will be appreciably reduced). This reduction in sensitivity may be overcome by effectively reducing the duration of the unquenched interval of the superregenerator. I have found it desirable, for example, to make the unquench interval of the same order of magnitude as the time required for oscillations in the tank circuit to build up to the overload condition in the absence of any appreciable signal externally applied to the tank circuit. If, for example, the unquench interval is made equal to the time required for oscillations to build up to overload in the absence of received signal, the envelope of oscillations in the tank circuit corresponding to no externally applied signal will be as represented at D in Figure 2. Similarly the envelope corresponding to the presence of externally applied signal at the time of unquenching will be as represented at E in Figure 2. Clearly the percentage difference in area under these two envelopes will be greater than in the instances represented at B and C. A cycle counter of the form shown in Figure 1 will be capable of developing a much greater difference in outputs for the two conditions.

Without reducing the actual duration of the negative unquenching pulses applied to the superregenerator of Figure 1, the effective duration of the unquenched interval can be reduced by the action of RC circuit 15, 16 and diode 14. While the quenching wave form is at a value of 250 volts, diode 14 will conduct and a corresponding voltage will be developed across condenser 16. Triode 1 will be in a zero bias condition because of the fact that the lower end of grid leak 13 will be effectively connected directly to ground through the diode, and accordingly no grid bias will be developed inasmuch as oscillations are prevented by the damping applied to tank circuit 2. As the voltage applied to the plates of diodes 8 and 9 commences to decrease upon the inception of the unquench interval, the plate of diode 14, due to the action of RC circuit 15, 16 which has a relatively long time constant, will go negative by a corresponding amount so as to cut off diode 14. Initially there will be no change in the bias applied to the grid of triode 1 since, for small changes in applied bias introduced in series with an oscillator grid leak, the tube will tend to readjust itself by change in grid current to the pre-existing bias condition. As the reduction in quenching voltage continues, diodes 8 and 9 will be cut off so as to remove the damping and per-

mit oscillations to build up in tank circuit 2. The negative biasing voltage developed across diode 14 will continue to increase until a point is reached at which tube 1 is no longer able to compensate for this increase in applied bias and oscillations will cease. In general this point will be reached at some time after the time at which the tank circuit is undamped, and I have found that the intervening interval is sufficient to permit the required buildup of oscillations in the tank circuit. The duration of this interval can be controlled by varying the slope of the unquenching pulses, by varying tube characteristics and by adjustment of the biasing voltage applied to diodes 8 and 9 from voltage divider 11, 12. Thus, if desired, the interval may be made of the same order of magnitude as the time required for oscillations to build up in the tank circuit 2 in the absence of externally applied signal.

With the circuit as described operating at an oscillator frequency of 60 megacycles per second and with an effective unquench interval of 1 μ second duration, a bandwidth of 3 megacycles per second was achieved. Furthermore it was found that, because of the relatively short unquench interval, a higher plate voltage could be used without exceeding the permissible plate dissipation of the oscillator tube. With higher plate voltage, a larger negative conductance is obtainable which further tends to increase the bandwidth.

Although, as illustrated in Figure 2, the interval, during which oscillations are permitted to build up and exist in tank circuit 2, is made equal to the time required for oscillations to build up to overload in the absence of signals impressed on the tank circuit from an external source, the duration of this interval may be varied appreciably while still retaining the advantages of operation in accordance with the invention. Thus, under certain circumstances, it may be found desirable to make the effective unquenched interval appreciably shorter, corresponding to time T_2 as shown in Figure 2; while under other circumstances it may be desirable to make the interval somewhat longer, corresponding to time T_3 . In varying the duration of the interval, however, it should be borne in mind that permitting oscillations to continue after overload has been reached will, in general, tend to reduce the difference between the output in the presence and in the absence of externally applying signal. Furthermore, it may be noted that, if logarithmic output versus input is desired, the unquenching interval should be of duration at least sufficient to permit oscillations to build up to overload in the presence of an externally applied signal of maximum amplitude.

Alternatively, the results achievable from the circuit of Figure 1, which are independent of the duration of applied negative unquenching pulses, may be obtained in accordance with the invention by applying, to any superregenerative receiver, negative unquenching pulses having leading edges of the desired steepness, and of duration equal to that required to effect the desired mode of operation. Thus, in order to secure the mode of operation represented at D and E of Figure 2, negative pulses corresponding to the one represented at F in Figure 2 might be applied to a superregenerative oscillator such as the one shown in Figure 4. This circuit differs from that of the schematic of Figure 1 only in the omission of diode 14 and RC circuit 15, 16 and in the use of self bias for diodes 8 and 9 derived from

RC circuit 11, 12 in lieu of bias from an external source. The proper duration and steepness of unquenching pulses may be obtained through the utilization of any conventional means external to

5 the oscillator circuit. Thus, as set forth in the aforementioned copending applications, if unquenching pulses of longer duration and insufficient steepness are available, they may be shortened and steepened by differentiation to yield 10 pulses of the desired duration and steepness.

Returning now to consideration of the cycle counter circuit shown in the schematic of Figure 1, for deriving an output signal from tank circuit 2 of the superregenerative oscillator, this circuit 15 operates to develop across condenser 20 an integrated unidirectional potential which increases with the number and amplitude of individual cycles of the signal appearing in the oscillator tank circuit. Its operation is briefly as follows:

20 During each positive oscillator cycle, condenser 20 is charged through condenser 17 and diode 19. If condenser 20 is made 100 times as large as condenser 17, an increment equal to 1/101 of the peak tank circuit voltage will be developed across 25 condenser 20 during each cycle. It will thus be apparent that the magnitude of condenser 17 should be small by comparison with that of condenser 20. On negative half cycles condenser 17 will be discharged through diode 18. The voltage developed across condenser 20 will approach the peak tank circuit voltage after a sufficient number of cycles. Thus, with a signal in the tank circuit of 1 μ second duration, corresponding to that shown at E in Figure 2, there may be 30 the equivalent of 60 complete half cycles at the oscillator frequency of 60 megacycles. This will result in the development, across condenser 20, of a voltage equal to 0.6 of the peak tank voltage. In the absence of any applied signal, on the other hand, the tank circuit signal may be equivalent to only five complete half cycles, and the voltage developed across condenser 20 will be 0.05 times the peak tank voltage. If the peak tank voltage is 10 volts, an increase of 6 volts will be developed in the presence of signal. The time constant of the circuit comprising condenser 20 and resistor 21 should be relatively long compared to the unquenched interval but short by comparison with the interval between unquenching pulses.

50 I claim:

An electrical circuit for detecting the energy content of successive pulses of oscillatory energy, said pulses having a predetermined maximum duration and a predetermined minimum time-spacing therebetween, said circuit comprising: 55 a pair of input terminals for said successive pulses of oscillatory energy; a charging condenser and a first unilateral conductive device serially connected between said input terminals; a series combination of a storage condenser and a second unilateral conductive device connected in parallel with said first unilateral conductive device, unlike elements of said first and second unilateral conductive devices respectively being connected together at the common connection of said charging condenser and said first unilateral conductive device, the capacity of said storage condenser being large compared to the capacity of 60 said charging condenser; and a resistor connected in parallel with said storage condenser, the value of said resistor being such, in relation to the capacity of said storage condenser, that the time constant of said resistor and said storage condenser is longer than said maximum 65 70 75

duration of said pulses of oscillatory energy and shorter than said minimum time-spacing between said pulses, whereby pulses of voltage are produced across said resistor whose respective peak amplitudes are measures of the energy content of corresponding oscillatory pulses supplied to said input terminals.
